UNITED STATES PATENT OFFICE

PAUL H. HORWITT, OF HARTSDALE, NEW YORK, ASSIGNOR TO THE MENASHA PRODUCTS COMPANY, OF MENASHA, WISCONSIN, A CORPORATION OF WISCONSIN

DISPENSER

Application filed February 20, 1931. Serial No. 517,134.

This invention relates to a napkin dispenser, and more particularly to a dispenser of the type having two opposite dispensing openings.

It is an object of this invention to provide a napkin dispenser having pivoted closure members at its ends so that the dispenser may be readily refilled.

It is a particular object of this invention to provide a novel form of dispenser having closure members pivoted to the base thereof and latched to the top thereof, so that the closure members may be swung downwardly to facilitate the refilling of the dispenser.

It is another object of this invention to provide a napkin dispenser which may be opened for refilling without it being necessary to move it from the surface upon which it rests.

It is a further object of this invention to provide a napkin dispenser in which there is a pair of gravity actuated followers.

These and other objects of my invention will be apparent from the following description and appended claims.

My invention (in a preferred form) is described in the following specification and in the drawing which form a part thereof.

On the drawing:

Figure 1 is an end elevational view of a napkin dispenser embodying my invention.

Figure 2 is an enlarged sectional view taken on the line II—II of Figure 1.

Figure 3 is a sectional view taken on the line III—III of Figure 3.

As shown on the drawing:

My dispenser comprises a container having a base 1, side walls 2, and top 3. The container is preferably formed of seamless metal. Suitable pads or buffers 1a are attached to the base 1 for supporting the container. A liner 4 is provided adjacent the base, and is spaced therefrom to receive the flanges 5 of the hinges 6.

The container is provided with closure members 7 at its ends having inturned flanges

8 which fit over the top 3 of the container. Flanges 9 of the hinge 6 are suitably secured, as by welding to the lower ends of the closure members.

The hinge 6 is of a common type of construction. The flanges 5 and 9 are rolled at their adjacent ends to form aligned beads 10 for the reception of pintles 11.

Each closure member 7 is provided with a window or opening 12. The metal adjacent the opening is rolled to form a protective bead 13. An angle member 14 is welded or otherwise suitably secured to the top of the end member. One flange of the angle member 14 extends inwardly and is provided with an opening 14a for the reception of a latch member.

A U-shaped bracket 15 is rigidly secured to the inside of the top 3, centrally thereof. A pin 16 is secured to the sides of the bracket. A latch member 17 is pivotally mounted on the pin. The latch 17 extends toward the end member and is provided with a depending portion 18 which fits into the opening 14a to thus hold the end member 7 against the container.

A coil spring 19 is mounted on the pin 16 to urge the latch 17 into engagement with the opening 14a in angle member 14.

While I have described the construction of but one end, it will be understood that the other end and latch is constructed in exactly the same manner.

Spaced lugs 20, three in number, are struck up from the liner 4. Pins 21 and 22 are supported in the lugs so as to be on either side of the middle lug 20 and also on either side of the transverse center line of the container.

Followers 23 and 24 are mounted on the pins 21 and 22, respectively. Each follower comprises a plate 25 of substantially the width of the container and of substantially half the depth of the container. The plate 25 is slightly rounded to present a convex face toward the adjacent end member. A narrow

strip 26 integral with the plate member extends downwardly therefrom and is rolled at its lower end to form a bead 27 for the reception of the pintle 21. The follower 24 is 5 similarly mounted on the pintle 22.

Stops 28 are secured to the side walls 2 and 3 respectively at their vertical center line. These stops extend outwardly from the walls 10 for a short distance and downwardly to approximately the lower ends of plates 25 thus dividing the container into two compartments.

Angle members 29 are welded or otherwise secured to the sidewalls 2. A flange 31 of 15 each angle member 29 extends outwardly from each wall to prevent the napkins 30 from interfering with the latches 17.

In operation a person may place his finger 20 through the opening 12 and release the latch 17. The end member 7 is then free to swing downwardly to the support upon which the dispenser rests. Napkins 30 may then be inserted through the end of the container and against the follower 24. The follower 24 will 25 accordingly be pushed back until when a sufficient number of napkins are inserted into the container, the follower will rest against the stops 28. The end member may then be swung to closed position. A similar procedure 30 is followed to fill the other side of the container.

The follower 23, located on one side of the stops 28, is attached to the pin 21 on the other 35 side of the stop. Similarly the follower 24 and pin 22 lie on opposite sides of the stops 29. Consequently, the followers will always be in an inclined position. As each napkin is removed, the force of gravity acting on the follower will urge it forwardly and downwardly and thereby urge the remaining napkins toward the end of the container.

The particular type of napkin used does 45 not form a part of my present invention. A napkin having two transverse folds so as to leave a body portion and tab portion on either side thereof is preferable. Such a napkin presents a tab portion, such as indicated at 30, which may be easily grasped through the window provided in my improved dispenser.

50 It will be seen that I have provided a strong durable dispenser which may be readily opened for inserting napkins therein, and which is a useful and compact article.

While I have described a preferred embodiment 55 of my invention, I do not wish to be limited thereto as I am aware that many changes may be made in the details of construction and arrangement of parts without departing from the spirit and scope of my 60 invention.

I claim as my invention:

1. A napkin dispenser comprising, a container, removable closure members at the 65 ends of the container, stop members attached to the walls of the container, said stop mem-

bers dividing the container into two napkin containing compartments, a follower pivoted to the base in each compartment and inclining upwardly into the opposite compartment, said followers being actuated by gravity to fall downward and outwardly to thereby urge the napkins toward the closure members. 70

2. A napkin dispenser comprising, a container having windows in its ends, lugs struck up from the bottom of said container, pins mounted in said lugs, gravity actuated followers mounted on said pins, said followers inclining toward the ends of the container, and stop members attached to the side walls 80 to prevent said follower from assuming a vertical position. 75

3. A napkin dispenser comprising, a container having windows in its ends, stop members extending from the side walls of said container centrally thereof, and gravity actuated followers pivoted to the base of the container at either side of the stop members, said followers inclining upwardly to the opposite sides of the stop members to urge the 90 napkins against the ends of the container. 85

4. A napkin dispenser comprising, a container, closure members having windows therein pivoted to the respective ends of the base of the container, latch receiving members attached to the insides of said closure members adjacent the top thereof, latches pivoted to the top of the container and extending toward each closure member respectively, depending portions on said latches for 100 engaging said latch receiving member to thereby hold said closure members against the container angle members attached to the side walls of said container, said angle members having flanges extending inwardly adjacent the top of the container for preventing the napkins from interfering with latches, stop members attached to the side walls of the container centrally thereof for dividing the container into two compartments, a follower 105 pivoted to the base of the container in each compartment, each follower inclining upwardly into the next compartment for urging the napkins against the adjacent closure member. 110

5. A napkin dispenser comprising a container having windows at its ends, stop members extending from the side walls of said container centrally thereof, lugs struck up from the bottom of said container, pins mounted in said lugs, said pins being out of alignment and on either side of the stop members, members mounted on said pins and extending upwardly to the opposite side of said stop members and followers integral with 120 said members and adapted to urge a plurality of napkins towards the adjacent end of the container. 115

6. A compact napkin dispenser comprising a container having windows at its ends, 125

stop members extending from the side walls of said container centrally thereof and dividing the container into two compartments, followers in each compartment having integral arms extending downwardly into the opposite compartments and pivoted to the base member so that the followers are urged toward the ends of the container by gravity.

In testimony whereof I have hereunto subscribed my name at New York, New York County, New York.

PAUL H. HORWITT.
